UNITED STATES PATENT OFFICE.

GEORGE L. MINNS, OF CLEVELAND, OHIO.

REPEATER ATTACHMENT FOR PHONOGRAHS.

1,214,352.

Specification of Letters Patent. Patented Jan. 30, 1917.

Application filed August 19, 1916. Serial No. 115,896.

To all whom it may concern:

Be it known that I, GEORGE L. MINNS, a citizen of the United States, residing at Cleveland, in the county of Cuyahoga and 5 State of Ohio, have invented certain new and useful Improvements in Repeater Attachments for Phonographs; and I do hereby declare the following to be a full, clear, and exact description of the invention, such 10 as will enable others skilled in the art to which it appertains to make and use the same.

This invention relates to new and useful 15 improvements in repeater attachments for phonographs and the principal object of the invention is to provide a device which may be attached to an ordinary phonograph using a disk record which is adapted to return the reproducer to playing position 20 after the record has been completed.

Another object of the invention resides in the provision of a novel means for raising the tone arm to cause the same to move back to playing position after the record has been 25 played.

A still further object of the invention is to provide a device consisting of a bar attached at its outer end to a post and carrying at its inner end a latch mechanism for 30 engaging a post at the center of the record which is screw threaded so that when said latch is in engagement and the record in motion, the inner end of the bar will be raised to lift the tone arm into such position 35 as to cause the stylus to disengage the record and after lifting said tone arm up to or beyond a predetermined point it will be seen that the same will gravitate back to starting position and engage another latch 40 mechanism which will allow the bar to descend to original position.

With these and other objects in view the invention consists in the novel combination and arrangement of parts which will be 45 fully set forth in the following specification and accompanying drawings, in which:—

Figure 1 is a top plan view of a phonograph showing this attachment in place thereon. Fig. 2 is an enlarged sectional view on line 2-2 of Fig. 1. Fig. 3 is an enlarged longitudinal sectional view of the traveler bar over which the tone arms move. Fig. 4 is a horizontal sectional view on line 4-4 of Fig. 2. Fig. 5 is an enlarged fragmentary sectional view through the traveler bar illustrating one of the latch mechanisms, 50 and Fig. 6 is an enlarged sectional view on line 6-6 of Fig. 2.

Referring to the drawings the numeral 1 designates the phonographic box of ordinary construction provided with the usual turn table 2 having the ordinary central post 3 which is connected to a suitable driving mechanism by means of which the turn table is rotated. A threaded sleeve 4 is 60 fitted over the upper end of said post and provided at its base with a flange 5.

Attached to and extending upwardly from the box 1 adjacent the periphery of the turn table 2 is a post 6 provided with 70 an internally screw threaded bore 7 into which a screw 8 is threaded. This screw 8 is surrounded by a compression coil spring 9 and the head 10 of said screw is seated on the upper side of the traveler bar which 75 will be more fully hereinafter described.

The traveler bar above referred to is designated by the numeral 11 and is provided at one end with an opening 12 through which the screw 8 extends and this bar is 80 supported on the upper end of the spring 9 as clearly shown in Figs. 2 and 6. This traveler bar 11 comprises a tubular body 13 formed intermediate its ends with a depression 14 which is arranged so that when said 85 bar is in place the depression will come in direct alinement with the outer groove of the playing surface of the record. Formed within the body 13 near the end opposite that which is connected to the screw 8 is an 90 inwardly extending annular flange 15 forming a central guide opening 16 through which the toothed latch member to be more fully hereinafter described is passable. Formed centrally of the upper side of the 95 depression 14 is an opening 17 through which the stem of the latch button is slid-able. A suitable slot 18 is formed near the inner end of the body 13 and this slot is to accommodate the box member for holding 100 the toothed bolt away from engagement with the sleeve 4.

The toothed bolt above referred to consists of a stem 19 provided at its outer end with a head 20 which is provided on its 105 outer face with a plurality of transversely extending ribs or teeth for coöperation with the threads of the sleeve 4. The stem 19 is slideable through the opening 16 and a spring 21 bears against the annular rib 15 110 and the head 20 to normally urge the bolt outwardly. The inner end of the stem 19

is provided with an upwardly extending lug 22 for coöperation with the dog 23 formed on the end of the lever 24 which is pivoted in the slot 18. A suitable leaf spring 25 normally urges the longer end of the lever 24 upwardly so as to move the dog 23 into engagement with the lug 22. It will thus be seen that when the device is in the position shown in Fig. 3 the head 20 will be held out of engagement with the threaded sleeve. It will also be seen that the lever 24 is curved upwardly to form a seat in which the tone arm when at its innermost limit of travel engages.

Connected to the inner end of the bolt 19 is a rod 26 which extends through the tubular body 13 and has pivotally connected to its inner end the arm 27 of a bell crank designated generally by the numeral 28 which is pivoted as shown at 29 within the depressed portion 14 of the bar 13 and the forwardly extending arm 30 of said bell crank is provided with a slot 31 for the reception of the pivot pin 32 by means of which the lower end of the stem of the button designated by the numeral 33 is pivoted to the bell crank. The upper end of the stem of the button is provided with a head 34 which is curved to form a seat in which the tone arm rests when at starting position. It will thus be seen that when the tone arm is set at starting position the same will operate to move the bell crank into such a position as to withdraw the bolt out of engagement with the sleeve 4.

It will be apparent from the foregoing that in use the tone arm rests when in starting position directly over the latch button 34 and as the record rotates, the tone arm 34 travels inwardly toward the center of the record and toward the latch 24. After the record has been played it will be seen that the tone arm will have been carried into engagement with the latch 24 and thus operating the same to release the bolt 19 and allow the heads 20 to engage the threaded sleeve 4 which due to the continuous rota-

tion of the turn table and disk will carry the end of the arm 11 upwardly until it reaches such position that the tone arm will by gravity travel to its original position and drop into the depression formed in the arm 11 thereby engaging the head 34 and causing the bell crank 28 to be operated to exert pull on the rod 26 and thereby withdraw the bolt 19 and allow the end of the arm 11 to drop to its original position. In this way it will be seen that the operation may be repeated until stopped by the user.

While in the foregoing there has been shown and described the preferred embodiment of this invention, it is to be understood that such changes may be made in the combination and arrangement of parts as will fall within the spirit and scope of the invention as claimed.

What is claimed is:—

The combination with a phonograph including a turn table, a central post in the turn table, a tone arm, a record on the turn table and a sound box on the tone arm, of a horizontally disposed traveler bar positioned beneath the tone arm, a sleeve fitted over the central post of the turn table and being provided with external screw threads, means adjustably supporting the outer end of the traveler bar and a toothed bolt at the inner end of the traveler bar for engagement with the sleeve so that when the sleeve rotates and the bolt is in contact therewith the traveler bar will be raised, a spring for raising said bolt into engagement with the sleeve, a latch for holding said bolt out of engagement with the sleeve, said latch being mounted at the inner end of the traveler bar and a push button at the opposite end of the traveler bar to pull the bolt back when the tone arm is in starting position.

In testimony whereof I affix my signature in presence of two witnesses.

GEORGE L. MINNS.
